1114.

UNITED STATES PATENT OFFICE.

HAUNCHEN SCHAAP, OF BINGHAMTON, NEW YORK.

DESIGN FOR A TOP FOR PILLOWS OR CUSHIONS.

SPECIFICATION forming part of Design No. 34,517, dated May 14, 1901.

Application filed April 10, 1901. Serial No. 55,257. Term of patent 3½ years.

To all whom it may concern:

Be it known that I, HAUNCHEN SCHAAP, a citizen of the United States, residing at Binghamton, New York, have invented and produced a new and original Design for Tops for Pillows, Cushions, and the Like, of which the following is a specification, reference being had to the accompanying drawing, in which the figure represents the design as applied to the surface of a pillow or cushion.

The leading feature of the design is in the representation of a crown in the center of the pillow or cushion.

As shown at A, the crown is represented as having a star arranged centrally of the front thereof, with two smaller stars upon each side. Beneath the position of the crown is a larger star independently arranged, and ad-

jacent to the detached star and crown is a scepter. At the lower left-hand corner is the representation of a cup, and at the upper right-hand corner clusters of full ears of grain are represented. In the left-hand upper corner is the representation of a sword, and extending along the top are represented a series of flowers of different varieties. In the lower right-hand corner there is represented a broken column.

What I claim is—

The design for a pillow or cushion top as herein shown and described.

HAUNCHEN SCHAAP.
